FRANK N. WEIS AND WILLIAM C. WEIS, OF MONROE, MICHIGAN, ASSIGNOR TO THE WEIS-VAN WORMER COMPANY, OF MONROE, MICHIGAN, A CORPORATION.

TOOL FOR APPLYING CLOSURES TO PAPER BOTTLES.

1,199,953.

Specification of Letters Patent.

Patented Oct. 3, 1916.

Application filed June 4, 1914. Serial No. 842,830.

To all whom it may concern:

Be it known that we, FRANK N. WEIS and WILLIAM C. WEIS, citizens of the United States, residing at Monroe, in the county of Monroe and State of Michigan, have invented certain new and useful Improvements in Tools for Applying Closures to Paper Bottles; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

In the patent issued to Andrew L. Weis for closure for paper packages, May 5th, 1914, No. 1,095,535, is disclosed a closure or stopper for paper bottles which renders such package substantially air-tight, the closure being applied in such manner that it can not be removed without either destroying the stopper or rupturing the package in such manner as to prevent the improper re-use of the package. The closure consists of a cup-shaped piece of stout paper the body of which fits into the mouth of the bottle, and having a flange which overlaps the outer margin of the mouth of the bottle. The present invention is designed to furnish a tool for expanding that portion of the cup-shaped stopper which projects into the bottle so that the stopper can not be withdrawn without rupturing the mouth of the bottle, and at the same time pressing the flange of the stopper onto the margin of the mouth of the bottle so that the meeting portions of the bottle and stopper form a practically liquid-tight joint.

To this end our invention consists of the devices, construction and arrangement of parts hereinafter described, and shown and illustrated in the accompanying drawings, in which—

Figure 1, is a side-elevation of our tool, partly in central vertical section, showing the flange expanding-fingers and spreading-plunger in position to enter the cavity of the stopper hereinafter described; Fig. 2, a top-plan-view of our implement; Fig. 3, a central vertical sectional elevation of a portion of our tool with the spreading-plunger retracted and with the expanding-fingers spread apart; Fig. 4, a view of one

of the expanding-fingers hereinafter referred to, detached; Fig. 5, a top-plan-view of a spring hereinafter referred to, and Fig. 6, a central vertical sectional elevation of a stopper,—detached and unexpanded,—
of the sort upon which our tool is intended to be employed.

Like numerals of reference indicate like parts throughout the drawings.

In the drawings, 1 and 2 are a pair of handles adapted to be conveniently grasped in one hand, pivoted together near their forward end, as at 3, upon a lug 4 formed upon the lower handle 1. These two handles are held normally separated at their rear ends by an interposed coiled spring 5. At the forward end of the handle 2 is pivoted, as at 6, the upper end of a plunger 7 having at its lower end an outwardly flared portion 8. In an opening through the handle 1, between the lug 4 and its forward end, is secured, by means of a setscrew 9, a piece 10 having formed thereon a collar 11 which abuts upwardly against the under side of the handle 1, and having also a collar 12 of less diameter than the collar 11, there being between the two collars an annular recess 13.

14 is a sleeve having therethrough a cylindrical bore the top of which embraces and tightly fits the shoulder 11. In the bottom edge of the member 14 is a groove 15, angular in cross-section, designed to receive with a snug fit the outer angle 16 of the side and flange of the bottle-stopper 17.

18—18 are pieces which may be regarded as longitudinal segments of a cylinder. These are located in the annular space between the plunger 7 and the sleeve 14. The inner sides of the parts 18 are notched near their upper ends, as at 19, to form hook-like projecting portions 20 which engage the annular space 13 in the member 11. The parts 18 which we call fingers and which may be of any desired number,—in the present instance four,—are by means of the hook-like portions 20 thus suspended in the annular space surrounding the plunger 7, there being room for slight radial swing of the fingers at their lower ends. At their lower inner edges the fingers 18 are beveled to fit against and correspond to the flaring surface 8 of the plunger 7. The outer edges of the fingers 18 are correspondingly notched as at 21 to form a

circumferential groove around the several fingers, in which groove is disposed a ring 22 forming a spring which holds the lower ends of the several fingers normally pressed inwardly against the inclined sides of the lower part of the plunger 7. At bottom each of the pieces 18 is provided with an outwardly projecting flange-portion 23, the several flange-portions forming, when the plunger is not retracted, a substantially circular rim.

The operation of our device is as follows: The body of the stopper being forced into the mouth of the bottle with its flange resting upon the top of the bottle, the handles 1-2 being separated, as in Fig. 1, the flange formed by the projecting parts 23 of the fingers 18, and which snugly fits the cavity of the stopper, is pressed down into the cup-like interior of the stopper. Now the handle 2 is pressed down onto the handle 1, forcing the plunger 7 upwardly and by the wedge-like action of the parts 8 upon the beveled inner edges of the pieces 18 forcing them asunder so that the spreading flange-parts 23 expand the walls of the stopper within the bottle. At the same time the angular recess 15 takes the flange of the stopper and the foot of the sleeve 14 presses down upon the top of the flange of the stopper which is thus squeezed between the bottom of the sleeve and the top of the flange-parts 23. The stopper is now so expanded and shaped that it conforms to the hole in the bottle and to the top of the bottle and forms a practically liquid-tight closure. When the handle 2 is released it is forced away from the handle 1 by the spring 5, thus restoring the parts to their positions indicated in Fig. 1 and freeing the bottle from the tool.

Having described our invention, what we claim and desire to secure by Letters Patent, is—

1. In a device of the described character, a pair of pivotally connected handles capable of mutual relative movement, a sleeve mounted upon and movable with one of the handles, a plunger in said sleeve, connected to and movable with the other handle, said plunger having at its outer end a flaring surface, and a plurality of fingers disposed in the annular space between the plunger and the sleeve and contacting with said flaring surface, said fingers having at their outer ends radially projecting flange portions in operative relation to the outer end of the sleeve.

2. In a device of the described character, a pair of pivotally connected handles capable of mutual relative movement, a sleeve mounted upon and movable with one of the

handles, a plunger in said sleeve, connected to and movable with the other handle, said plunger having at its outer end a flaring surface, a plurality of fingers disposed in the annular space between the plunger and the sleeve and contacting with said flaring surface, said fingers having at their outer ends radially projecting flange portions in operative relation to the outer end of the sleeve, means for holding the hand portions of said handles normally separated, and means for holding said flange portions normally radially retracted.

3. In a device of the described character, a pair of pivotally connected handles, a sleeve carried by one of said handles and having a grooved lower edge, a series of fingers in said sleeve pivotally supported at their upper ends and having radial flange-portions below the grooved edge of the sleeve, means actuated by the other of said handles for radially projecting said flange-portions and a spring which holds said flange-portions normally retracted.

4. In a device of the described character, a pair of pivotally connected handles capable of mutual relative movement, a sleeve mounted upon and movable with one of the handles, a plunger in said sleeve, connected to and movable with the other handle, said plunger having at its outer end a flaring surface, and a plurality of fingers disposed in the annular space between the plunger and the sleeve and contacting with said flaring surface, said fingers having at their outer ends radially projecting flange portions in operative relation to the outer end of the sleeve.

5. In a device of the described character, a pair of pivotally connected handles capable of mutual relative movement, a sleeve mounted upon and movable with one of the handles, a plunger in said sleeve, connected to and movable with the other handle, said plunger having at its outer end a flaring surface, a plurality of fingers disposed in the annular space between the plunger and the sleeve and contacting with said flaring surface, said fingers having at their outer ends radially projecting flange portions in operative relation to the outer end of the sleeve, means for holding the hand portions of said handles normally separated, and means for holding said flange portions normally radially retracted.

In testimony whereof we affix our signatures in presence of two witnesses.
